UNITED STATES PATENT OFFICE.

EDWARD SUTTON, OF BROOKLYN, NEW YORK.

FIRE-ESCAPE.

SPECIFICATION forming part of Letters Patent No. 369,137, dated August 30, 1887.

Application filed May 5, 1887. Serial No. 237,215. (No model.)

To all whom it may concern:

Be it known that I, EDWARD SUTTON, of Brooklyn, in the county of Kings and State of New York, have invented a new and Improved 5 Fire-Escape, of which the following is a full, clear, and exact description.

Reference is to be had to the accompanying drawings, forming a part of this specification, in which similar letters of reference indicate 10 corresponding parts in all the figures.

Figure 1 is a side elevation of my invention applied to a ladder. Fig. 2 is a front elevation of the same. Fig. 3 is a plan view of the fire-escape without the ladder. Fig. 4 is an 15 enlarged sectional elevation taken on the line $x-x$ of Fig. 3. Fig. 5 is an enlarged detail-side view of the winding-drum, and Fig. 6 is a sectional plan view of the upper end of the ladder.

20 The invention will first be described in connection with the drawings, and then pointed out in the claims.

A A represent the side pieces of the main frame of the fire-escape. These side pieces are 25 of cast-iron joined together by the rods B B, and in these side pieces is journaled the shaft C, on which is secured the brake-drum D and the ratchet-wheel E. At the sides and base of the side pieces, A, are cast the cleats a a, which 30 receive the lower ends of the ladder F, and hence the frame of the fire-escape becomes the support for the ladder, as will be understood from Figs. 1 and 2, the bottoms of the side pieces, A, being flanged, as shown at a' a', for 35 supporting the ladder.

Upon the shaft C, between the brake-drum D and the ratchet-wheel E, is placed loosely the drum G, upon which is wound the rope H. This rope reaches from the drum G up over 40 the pulley J, placed upon the rod K, attached to the top of the ladder F. Upon the drum G is placed another rope, L. This is wound in the opposite direction from the rope H, so that when the rope H is paid out the rope L will 45 be wound up, and vice versa. Over the drum D is placed the strap M, which is attached at one end to the pin b in one of the side pieces, A, of the frame, and at the other to the lever N outside of the fulcrum c of said lever, so that 50 when said lever is pressed downward the strap M will be drawn in firm contact with the drum D, and thus act as a brake to prevent the rope

H from passing out too rapidly. Another strap, M', is attached at one end to the pin b, and at the other to the lower end of the lever 55 N, so that when the said lever is depressed at its outer end it will also bring the strap M' into contact with the drum D, so that with a single lever both straps M M' may be held in contact with the drum D, which constitutes a 60 very effectual brake. When any weight comes upon the rope H—that of a person, for example, descending from a burning building—the drum G will be locked to the shaft C by the click C', engaging with the ratchet-wheel E, so 65 that the weight will cause the said drum, the shaft C, and the drum D to revolve, all of which may be easily controlled by the lever N. The unwinding of the rope H from the drum G will wind the rope L on the drum G, 70 so that by simply pulling upon the rope L the revolution of the drum G may be reversed for quickly winding up the rope H.

The rod K is attached to the ladder by the cleats k k, which are divided, as shown at k', 75 to enter recesses k'', made in the uprights of the ladder, so that by simply slipping the cleats in place and placing the ladder upon the frame of the fire-escape, and passing the rope H over the pulley J, all will be in readiness for the 80 firemen to ascend the ladder and lower persons by the rope H, the fire-escape being operated by persons at the foot of the ladder.

Having thus fully described my invention, I claim as new and desire to secure by Letters 85 Patent—

1. The fire-escape herein shown and described, the same consisting of the frame A, provided with the cleats a, the ladder held by the said main frame and cleats, rods K, pulley J, shaft C, drum D, secured upon the shaft, the drum G, loose upon the shaft, the ratchet-wheel E, click C', ropes H L, brake-belt M, and brake-lever N, substantially as described. 90

2. The rod K, having the slotted keepers k 95 k, secured at its ends and provided with the pulley J, in combination with the uprights of the ladder, cut away at k'' to receive the keepers k', substantially as described.

EDWARD SUTTON.
